[57] CLAIM

The ornamental design for a carton for multiple individually packaged products, as shown and described.

DESCRIPTION

FIG. 1 is a perspective view of a carton for multiple individually packaged products showing our design;

FIG. 2 is a top plan view thereof;

FIG. 3 is a front elevational view thereof;

FIG. 4 is a back elevational view thereof;

FIG. 5 is a left end elevational view thereof;

FIG. 6 is a right end elevational view thereof; and,

FIG. 7 is a bottom plan view thereof.

The broken line showing of environment in FIGS. 1 & 2 is for illustrative purposes only and forms no part of the claimed design.
